UNITED STATES PATENT OFFICE.

LEON CLINE, OF CHICAGO, ILLINOIS.

DESIGN FOR A SHOWER-BATH RING.

SPECIFICATION forming part of Design No. 29,901, dated December 27, 1898.

Application filed October 31, 1898. Serial No. 695,132. Term of patent 7 years.

To all whom it may concern:

Be it known that I, LEON CLINE, a citizen of the United States of America, residing at Chicago, in the county of Cook and State of Illinois, have invented and produced a new and original Design for Shower-Bath Yokes, of which the following is a specification, reference being had to the accompanying drawings, forming a part thereof.

In said drawings, Figure 1 is a perspective view of the shower-bath yoke, showing the same as viewed from one side thereof. Fig. 2 is a plan view of the same.

As shown in the drawings, the leading or essential feature of my design consists of a tube A, bent to approximate a ring, as seen in the plan view, Fig. 2, and having its side portions bent in an upwardly-convex curve, so that the central parts of said side portions are in a plane at a considerable distance from a plane passing through the front and rear portions of the ring, the tube as a whole being so shaped as to approximately fit about the neck or upper part of the shoulders of the person on which the ring is placed. As seen in Fig. 1, which shows the article in its position when in use, the rear part of the ring is slightly below and the front part thereof very much below the level of the elevated or upwardly-curved side portions of the ring. Connected with the lower part of the front or

downwardly bent or deflected portion is a tubular part B, joined to the main or ring portion A and extending downwardly and forwardly therefrom. Said main or ring portion A is provided with a series of jet openings or apertures a. The parts A and B are made of a single tube and are continuous with each other and of uniform size. As shown in the accompanying drawings, the adjacent ends of the part constituting the ring A are not joined to each other at the front of the article, and the free end of said part A terminates in a small rounded knob a', so that said parts A and B have the form of a continuous bent tube bent into ring form and the ends of which are disconnected from each other at the front of the ring.

The leading or material feature of my design is the ring so bent as to form upwardly-curved side portions and downwardly-deflected front and rear portions, which give to the ring, as seen in side view, a distinctly arched or bowed form.

I claim as new and desire to secure by Letters Patent—

The design for a shower-bath ring, substantially as herein shown and described.

LEON CLINE.
